UNITED STATES PATENT OFFICE.

ALEC J. GERRARD AND PARVIN WRIGHT, OF CHICAGO, ILLINOIS.

WIRE STRAIGHTENING AND SWAGING MACHINE.

Application filed June 14, 1922. Serial No. 568,307.

To all whom it may concern:

Be it known that we, ALEC J. GERRARD and PARVIN WRIGHT, respectively a subject of the King of Great Britain and a citizen 5 of the United States, residing at Chicago, in the county of Cook and State of Illinois, have invented certain new and useful Improvements in Wire Straightening and 10 Swaging Machines; and we do hereby declare the following to be a full, clear, and exact description of the invention, such as will enable others skilled in the art to which it appertains to make and use the same.

This invention relates to a wire straightening and swaging machine and has for its 15 object to provide a machine which will be more efficient in action and less costly to construct than those heretofore proposed.

With these and other objects in view the 20 invention consists in the novel details of construction and combinations of parts more fully hereinafter disclosed and particularly pointed out in the claims.

Referring to the accompanying drawings 25 forming a part of this specification, in which like numerals designate like parts in all the views:

Figure 1 is a side elevational view of a machine made in accordance with this invention;

Figure 2 is a plan view of the parts shown in Figure 1;

Figure 3 is a sectional view taken on the line 3—3 of Figure 2 looking in the direction of the arrows;

Figure 4 is a sectional view taken on the line 4—4 of Figure 3 looking in the direction of the arrows;

Figure 5 is a detail view illustrating the 40 swaging and cutting dies;

Figure 6 is a view taken on the line 6—6 of Figure 4, looking in the direction of the arrows; and

Figure 7 is a detail view of the swaged 45 wire showing how the swaged parts are cut in two.

1 indicates any suitable base or support on which is mounted the shaft 2 of any suitable motor 3 provided with the power 50 pulley 4 around which passes the belt 5.

Said belt also passes over the power pulley 6 rigid with the power shaft 7 carrying the pinion 8, meshing with the gear 9, mounted on the short shaft 10, carried by the swinging arm 11, playing over the arc 12. Said 55 short shaft 10 is provided with the pinion 13 meshing with the gear 14, rigid with the shaft 15. The shaft 15 carries a pair of cams 16 and 17 as best illustrated in Figure 4, and above these cams is positioned the 60 swaging bar 18 provided with a plurality of die members 19 as shown. The said swaging bar is recessed at each end as indicated at 20 and 22, and into said recesses fit the springs 21, the upper ends of which 65 rest in the recesses 22 with which the cap members 23 are provided.

25 represents a stationary swaging bar provided with pivoted supports 26 resting in said cap members 23, and also carrying 70 at its lower surface the swaging die members 27 as shown. The cams 16 and 17 dip into the oil cups 30 carried by the brass bushings, and are thereby kept in condition. The wire 35 comes into the machine from 75 coils not shown, passes over pulleys 36, pivoted as at 37 to the levers 38, pivoted at 39 in the brackets 40 and provided with the notched trigger members 41. Coacting with each trigger member 41, is a pivoted trigger 80 42 rigid with the cutting member 43 into which the wire 35 passes into the machine and which is controlled by the spring 44. Should the wire in its travel become knotted or tangled, its pulley 36 will be 85 elevated which will depress its corresponding notch 41, thus releasing the trigger 42 which causes the cutter 43 to sever the same, and thus will the particular tangled wire not stop the operation of the machine. 90

After the wire 35 has thus passed the cutter 43 it enters the barrel 45 of the straightening mechanism 46, which is provided with the worm 47 engaging the gear 48, mounted on the shaft 49 operated by the 95 sprocket 50, see Fig. 2, rigid with the shaft 7 over which passes the belt or sprocket chain 51. Said chain 51 also passes over the sprocket 52 rigid with the shaft 49 and thus is the worm 47 and barrel 45 turned. The 100

wire after being straightened in the straightener 46 passes between the roll 55 and a plurality of short rolls 56. The roll 55 is continuous and is provided with grooved surfaces as best indicated in Fig. 3, while a plurality of short rolls 56 are mounted on short stud shafts 57 carried in the individual frames 58. Each of the short rolls 56 are provided with grooved surfaces 59 which are adapted to coact with the grooved surfaces of the rolls 55, and to frictionally engage the wire strands between them. Each of said rolls 56 is provided with a gear 60, as best shown in Figures 2 and 3, and the roll 55 is provided with a plurality of similar gears 61 which mesh with said gears 60 and thus are the individual short rolls 56 positively turned from the continuous longer roll 55. As will be readily understood from Fig. 2 of the drawings, there are a plurality of wires being drawn through a plurality of straighteners 46, and under a plurality of cutters 43, simultaneously.

25 After a wire strand 35 is thus forcibly drawn through its straightener 46, it is pushed forward by the said rolls 55 and 56 between the cutting and swaging dies 19 and 27, as will be clear from Figures 3 and 4.

30 The swaging die 27 is held stationary in its supporting bar 25 while the swaging die 19 is raised vertically by the action of the cams 16 and 17 to cut and deform the wire into the shape shown in Fig. 7. That is to say,

35 in the types of wire tying machines which have been recently developed, it is very desirable indeed that the tie wires be provided with the depressions such as 62 providing the holding shoulders 63 in each end of the wire and this machine accomplishes this purpose.

It is often convenient to change and to repair the cutting dies 19 and 27 and with the construction just illustrated, by loosening up a few bolts and nuts the bar 25 can be readily turned on its pivots 26 through an angle of 90° or 180° which not only exposes the die member 27, but also the die members 19. This movement of the bar 25 will be readily understood from the detailed view shown in Fig. 6, wherein there is shown a stationary stop member 81, adapted to contact with one side of the pivoted swaging bar 25, as well as a pivoted stop member 82 adapted to contact with the other side of said bar 25. The members 81 and 82 are conveniently secured to the cap member 23, and the member 82 is capable of swinging around its pivot 83, to release the bar 25 and permit it to swing from its full line position to its dotted line position shown in Figure 6.

During the cutting and swaging operation it is desirable that the motion of the various wires 35 be stopped and to this end

the swaging plate 18 is provided with the extension 65, best shown in Fig. 3, on which rests the set screws 66 with which the various individual frames 58 are provided. It thus results that when the swaging plate 70 or bar 18 is elevated to deform the wires 35, all of the frames 58 are raised at their ends carrying the screws 66 and the raising of these ends raises each individual short roll 56 a very slight distance.

75 This said distance is sufficient to decrease the friction between the several rolls 56 and the several surfaces of the roll 55 so that the various wires are stopped in their motion. The said frames 58 are pivoted on studs 96 indicated in Figures 1 and 2, to permit this slight movement. Said short frames 58 are also provided with adjustable screws 97 resting upon the frame work, as best shown in Fig. 1, in order that the desired friction on the wires may be accurately attained.

80 After the various wires 35 are thus deformed and severed in the manner disclosed, their cut ends are carried out of the machine by means of the rolls 70 and 71 mounted on the shafts 72 and 73, respectively. The shaft 72 is driven by the sprocket 75 rigid therewith, over which passes the sprocket chain 76 driven by the sprocket 77 rigid with the power shaft 7, as will be clear 85 from Fig. 2.

85 As these straightened cut and swaged tie wires are intended to band boxes and packages of various sizes, it is evident that a single length of wire would not be suitable for all purposes. Therefore, it is desirable to change the lengths of the wires cut by this machine. In order to do this, it is only necessary to change the multiplying gears 9 and 13. These said gears are carried on the lever like means 11 which is preferably made of two parallel arms as best shown in Fig. 4. These said arms carry the studs 80 between which are mounted the gears 9 and 13, so that it is only necessary to remove 90 the said gears and their pivot 10 and to substitute gears of the proper size to feed the desired lengths of wire through the swaging mechanism before the cutting action takes place.

95 It is obvious that those skilled in the art may vary the details of construction as well as the arrangement of parts without departing from the spirit of the invention, and therefore, it is desired not to be 100 limited to the above disclosure except as may be required by the claims.

105 What we claim is:—

110 1. In a wire cutting and swaging machine the combination of a wire straightening means; a wire feeding means; means to cut a tangled wire strand before it reaches said straightening means; and a reciprocating wire cutting and swaging means, substantially as described.

2. In a wire cutting and swaging machine the combination of a wire straightening means; a wire feeding means; means to cut a tangled wire strand before it reaches said straightening means; and a reciprocating wire cutting and swaging means comprising a rotating cam shaft and a reciprocating die member, substantially as described. 5
3. In a machine for simultaneously cutting and swaging a plurality of wires, the combination of a plurality of wire straightening means; a plurality of wire feeding means; a plurality of wire cutting means adapted to automatically sever tangled wires before they reach said straightening means; and cam actuated reciprocating wire cutting means, substantially as described. 10
4. In a machine for simultaneously cutting and swaging a plurality of wires, the combination of a plurality of wire straightening means; a plurality of wire feeding means; a plurality of wire cutting means adapted to automatically sever tangled wires before they reach said straightening means; and cam actuated reciprocating wire cutting means comprising stationary upper anvil members and movable lower cutting members, substantially as described. 15
5. In a machine for simultaneously cutting and swaging a plurality of wires, the combination of a plurality of wire straightening means; a plurality of wire feeding means; means to stop the feed of all the wires during the cutting operation; a plurality of wire cutting means, adapted to automatically sever tangled wires before they reach said straightening means; and cam actuated reciprocating wire cutting means adapted to control said means for stopping the wire feed, substantially as described. 20
6. In a wire cutting and swaging means the combination of a wire straightening means; a wire feeding means; means to cut a tangled strand before it reaches said straightening means; and a wire cutting and swaging means comprising a pivotally supported bar. 25
7. In a wire cutting and swaging means the combination of a wire straightening means; a wire feeding means; means to cut a tangled strand before it reaches said straightening means; a wire cutting and swaging means comprising a pivotally supported bar provided with a plurality of die members; and a reciprocating wire cutting and swaging means coacting with said bar. 30
8. In a wire cutting and swaging means the combination of a swaging bar provided with a plurality of die members; means for feeding a wire to be acted on by said bar; means for so pivoting said bar that it may be readily swung on its pivots; readily detachable locking means for normally holding said bar in a vertical position; and a reciprocating wire cutting and swaging means coacting with said bar, substantially as described. 35
9. In a wire cutting and swaging means the combination of a vertically reciprocating wire swaging bar provided with a plurality of die members; a normally stationary pivoted swaging bar adapted to be swung on its pivots when desired and provided with a plurality of die members adapted to coact with said first named die members; readily movable means for locking said last named bar in a vertical position; a spring for controlling the return of said first named bar; means for feeding a plurality of wires to be acted upon by said bars; and means for cutting a tangled wire before it reaches said bars. 40
10. In a wire cutting and swaging means the combination of a vertically reciprocating swaging bar provided with a plurality of die members; a normally stationary pivoted swaging bar adapted to be swung on its pivots when desired and provided with a plurality of die members adapted to coact with said first named die members; readily movable means for locking said last named bar in a vertical position; a shaft provided with a cam for reciprocating said first named bar; a bearing provided with an oil cup into which said cam dips; and a spring for returning said first named bar, substantially as described. 45
11. In a wire cutting and swaging means the combination of an upper pivoted and normally stationary wire swaging bar; a plurality of die members carried by said bar; means for feeding a wire to be acted on by said bar; a lower reciprocating swaging bar provided with a plurality of die members coacting with said first named die members; a cam shaft provided with a pair of cams for reciprocating said last named bar; and means for continuously rotating said shaft, substantially as described. 50
12. In a machine for feeding and cutting wires, the combination of means for straightening a plurality of wires; means for feeding a plurality of wires; means for simultaneously cutting a plurality of wires; and means for varying the lengths of the wires cut; and means for cutting a tangled wire before it is subjected to a straightening action. 55
13. In a machine for feeding and cutting a plurality of wires, the combination of means for simultaneously feeding a plurality of wires; means for simultaneously cutting a plurality of wires; means for continuously rotating said cutting and feeding means; and means to vary the rate of rotation of one of said last named means to vary the lengths of the cut wires; and means for cutting a tangled wire before it is subjected to a straightening action. 60

14. In a machine for cutting, straightening and feeding simultaneously a plurality of wires, the combination of means for simultaneously straightening a plurality of wires; means for feeding simultaneously the straightened wires; means for swaging and cutting simultaneously the fed wires; and means for varying the lengths of the wires

cut; and means for cutting a tangled wire before it is subjected to a straightening action. 10

In testimony whereof we affix our signatures.

ALEC J. GERRARD.
PARVIN WRIGHT.
